United States Patent Office

Des. 221,290
Patented July 27, 1971

221,290

DISH

Karl Wiedemann, 519 Fireside Lane,
Cherry Hill, N.J. 08034

Filed May 25, 1970, Ser. No. 23,205

Term of patent 14 years

Int. Cl. D7—01

U.S. Cl. D44—15

FIG. 1

FIG. 2

FIG. 3

FIG. 4

FIG. 5

FIG. 6

FIG. 7

FIG. 1 is a top plan view of a dish showing my new design;

FIG. 2 is a bottom plan view;

FIG. 3 is a side elevational view of FIG. 1;

FIG. 4 is a side elevational view of FIG. 1 rotated 90 degrees counterclockwise;

FIG. 5 is a side elevational view similar to FIG. 1 rotated 180 degrees;

FIG. 6 is a side elevational view similar to FIG. 1 rotated 90 degrees clockwise; and

FIG. 7 is a partial section on line 7—7 of FIG. 1.

I claim:

The ornamental design for a dish, substantially as shown.
